UNITED STATES PATENT OFFICE.

BEULAH G. LANCE, OF FULTON, CALIFORNIA.

STEEL-WOOL HOLDER.

Application filed February 5, 1923. Serial No. 617,021.

This invention relates to a holder for steel-wool or other scrubbing material and has for its objects to provide a convenient means to hold the scrubbing material, to 5 simplify the construction of devices of this kind and to provide means whereby the scrubbing material may be removed and a new supply secured to the holder.

With this and other objects in view which 10 will appear later in the specification, the invention consists of the novel features of construction illustrated in the drawings and more particularly pointed out in the claims.

In the accompanying drawings Figure 1 15 is a side elevation showing in dotted lines the means for securing the scrubbing material. Fig. 2 is a sectional view taken on dotted lines *a—a*, Fig. 4. Fig. 3 is a detail view of one set of hooks for securing the scrubbing material and Fig. 4 is a top view of the holder.

Referring to the drawings a knob 1 is 20 formed of any suitable material and is provided with a concave face on which soap 3 is placed. A pad of scrubbing material such as steel-wool for example, is secured to the concave face of the holder by means of hook arrangements 4 and 5 and the soap is held 25 between the face of the knob and the scrubbing material.

The hook means are composed of two sets, 30 4 and 5. In some instances, if desired, only one set may be used. Hook means 4 is spring like in its action and is secured to the holder 35 in grooves 8. It will be noted that when this hook means is pressed down the claws provided on its free ends will open outward as shown in dotted lines in Fig. 1, and when released will spring back to its original position, imbedding a part of the scrubbing 40 material into grooves 9.

Hook means 5 is substantially U-shaped but with its free ends bent to form claws. It 45 acts as a lever with the slotted holes 6 and 7 provided in the holder as its fulcrum points. Its movement is shown by dotted line in Fig. 1, and it is moved to this position before securing the scrubbing material. When it is in the position shown by dotted 50 lines the claws slant downward and to secure the scrubbing material the holder is

pressed onto the scrubbing material and at the same time pushed forward which will cause the claws to penetrate the scrubbing material; it is then brought to its normal position as shown in Figs. 1 and 4. It will be noted that the claws of hook means 4 are imbedded in grooves 9 and the claws of hook means 5 are drawn into the concave face of the holder when they are in their normal 55 position which is to prevent the claws from coming into contact with and scratching the object being cleansed or polished.

Having thus described my invention, what I claim and desire to secure by Letters Patent, is:—

1. A holder of the kind described, comprising a body having its lower face concaved, a spring clamping member straddling said body and provided at each end 70 with an inwardly directed hook for clamping cleansing material against the concave face of said body, said body being provided with spaced slotted openings therethrough, and an auxiliary clamping member of sub- 75 stantially inverted U-shape having its legs passed through the slots of said body, and provided with hooked ends for clamping the cleaning material against said body.

2. A holder of the kind described, comprising a body provided on its opposite sides with slots extending upwardly into the body and intersecting adjacent the top of the body, said body being further provided with a concave lower face, a spring member located in said slots and straddling said body and provided at its ends with inwardly directed hooks for clamping a cleaning material against said body, downward pressure on the spring member acting to disengage 90 the hooks from the cleaning material.

3. A holder of the kind described, comprising a body having spaced openings therethrough, a clamping member of substantially inverted U-shape having its legs 95 passed through the openings in said body and provided with hooked ends for clamping the cleaning material against said body.

In testimony whereof I have hereunto set my hand.

BEULAH G. LANCE.
